Theodore Halman Hinchcliffe, 1450 La Loma Road,
Pasadena, Calif.

Filed June 24, 1958, Ser. No. 51,500

Term of patent 7 years

(Cl. D43—1)

Fig. 1.

Fig. 3.

Fig. 2.

Fig. 1 is a front perspective view of a conveyer belt cleat showing my new design;

Fig. 2 is a rear perspective view thereof; and

Fig. 3 is a slightly reduced sectional view taken on the line 3—3 of Fig. 2.

The end of the conveyer belt cleat not shown is the same in appearance as the end shown.

I claim:

The ornamental design for a conveyer belt cleat, as shown and described.
